UNITED STATES PATENT OFFICE.

CLIFFORD HASTY KAIN, OF SAN CARLOS, CALIFORNIA.

ROTARY PUMP AND MOTOR.

Application filed July 2, 1924. Serial No. 723,807.

This invention relates to rotary motors and particularly to that type of converter in which rotation of a shaft is produced by means of reciprocating plungers working within cylinders, the latter being tangential to a circle concentric with the axis of the rotating shaft.

One of the objects of the invention is the provision of an improved rotor adaptable in its application to all uses of engines, motors, and pumps which are actuated mechanically or operated as mechanical converters.

A more specific object of the invention is the construction of a rotor carrying plungers which reciprocate in cylinders in paths tangential to a circle concentric with the axis of rotation of the rotor, whereby the maximum mechanical advantage is secured throughout the entire working strokes of the plungers, this being in favorable contrast with the stationary type of reciprocating pumps and engines in which maximum mechanical advantage is approached only at one point, about midway of the piston travel.

Still another object of the invention is to construct the rotary motor with the tangentially arranged plungers as aforesaid, the movements of said plungers being controlled by a control ring or equivalent member formed with a guiding curvature so designed that the plungers, in all positions of the rotor, react normally against said ring, avoiding negative tangential components which, in the aggregate, would detract materially from the force of the power stroke.

With a rotary motor built according to the present invention it is theoretically possible, neglecting friction, to obtain a mechanical efficiency of 100%.

In its broadest, and perhaps, most important aspect the invention contemplates the construction of a one-stage rotor the detail features of which may be varied to suit the exigencies of use. But in certain applications of the invention it may be built in two-stage units, reversely arranged. In this form, the applied power is divided between the two units, the working strokes of which take place through successive arcs of 180°,

the mechanical efficiency throughout each working stroke (neglecting friction) being sustained at substantially 100 per cent, so that not only is there no loss of head in the impelling fluid due to the negative components above referred to, but an evenness of torque is produced, both of these factors particularly adapting the motor to use as a rotor for fluid meters where maintenance, in so far as possible, of a uniform and unimpeded head of the impelling fluid is desired.

Summarizing the objects of the invention, they may be briefly classified as pumping actions, involving necessary suction and discharge connections and energy converting actions, with the necessary inlet and outlet connections. All other actions such as metering, compressing, power transmission and braking, are modifications of one or the other, or both of the principal objects involved.

In the drawings:

Figure 1 is a side elevation of a single stage device embodying the principles of my invention.

Figure 2 is a section taken along the line 2—2 of Figure 1.

Figure 3 is an end elevation viewed from the right-hand side of Figure 1, the rotor being removed.

Figure 4 is a plan view of one of the connecting plates.

Figures 5, 6 and 7 are respectively plan, section and end elevational views of the core or valve member.

Figure 8 is a side elevation of a two-stage rotor.

Figure 9 is a section taken along the line 9—9 of Figure 8.

Figures 10, 11 and 12 are elevational views of the core or valve member taken in three perpendicular planes.

Referring now in detail to the several figures, and first advertiring to that form of the invention which is embodied in the structure shown in the first seven figures, the numeral 1 represents a stationary frame which may be of any desired form and construction and which affords a support on one side for the bearing 2 which carries the drive shaft 3, the latter being fixed in any suitable manner to the rotary part of the

mechanism. A hub 4 passes through the opposite side of the frame co-axial with the drive shaft 3, said hub affording a bearing surface for the rotor and also cooperating with the latter in performing the functions of an inlet and a discharge valve. The hub is formed with a tapered face 5 which makes free running contact with a complementary face 6 of the rotor, the joint between said faces being practically fluid-tight. The rotor includes the cylinder block 7 having cylinder bores 8 the axis of said bores being tangential to a circle concentric with the axis of the drive shaft. The hub is formed with ports 9 opening in the tapered face thereof in the path of travel of the cylinder bores, said ports opening on opposite sides of the hub and being connected respectively with inlet and outlet channels 10 and 11, said channels preferably leading to that portion of the hub which lies external to the frame and being there connected to inlet and outlet conduits 12 and 13. As the cylinder block rotates the cylinder bores register successively with the inlet and outlet ports permitting the sequential filling and discharge of the cylinders. The plungers 14 are arranged to reciprocate within said cylinders, said plungers in the present instance being constructed as hollow members surrounding guiding tubes 15. The latter are pivotally carried by transverse bars 16, said bars being fixed at their opposite ends to the plates 17 and 18 which are carried at the sides of the cylinder block and secured thereto in any suitable manner. The guiding tubes 15 preferably extend a slight distance within the cylinder bores as here shown. The plungers 14 are each provided with oppositely disposed transverse pins 19 reciprocably movable in the slots 20 with which the side plates 17 and 18 are provided. The ends of said pin are pivotally mounted in bearing-apertures 21 formed in the outer ends of the connecting plates 22. The latter are formed with circular apertures 23 the peripheral walls of which bear upon eccentric rings 24 fixed in stationary relation at opposite sides of the frame 1. The rings 24 are eccentric respectively to the common axis of the drive shaft 3 and hub 4, so that when the cylinder block rotates around the axis of the drive shaft, the plungers at the same time will be rotated about the center of the eccentric ring, a reciprocating movement being given thereby to said plungers, within the cylinder bores. Appropriate packing 25 may be provided between the plunger and cylinder wall, adjacent the outer end of each cylinder and held in place by means of the packing gland 26.

It is apparent from the above construction that, whether operated as a pump or

motor, the cylinders and plungers are so arranged that the working stroke acts in a direction tangentially of the path of the crank arm throughout the entire range of the working stroke, the crank arm being the radius of the circle to which the axes of the cylinder bores are tangent. This is the most advantageous arrangement for the development of high efficiency since the turning moment is equal to the product of the force applied perpendicularly to the crank arm multiplied by the length of the crank arm. In the ordinary reciprocating motor or pump the position of tangency of the plunger with relation to the path of the crank arm is only realized at one point in the range of the stroke of the plunger, about mid-way of the range of travel of the plunger.

It is obvious in the present structural arrangement that the power within the cylinders reacts against the plungers, and through them against the eccentric rings, therefore it is readily seen, that if the plungers are so connected to the eccentric rings that the line of pressure acting through the plungers is practically normal to the eccentric rings in all positions of the plunger, the entire pressure of the plungers acting against the walls of the cylinder bores may be exerted against the outer end of the crank arm, giving maximum efficiency. But if the line of pressure acting through the plungers is not substantially normal to the eccentric rings the force of said plungers will be resolved into components, one of which is tangential to the eccentric rings and the other of which is expended in rotating the cylinder block. It thus becomes a very material and important part of the invention to have the eccentric rings of such shape and size that the plungers will be normal to them in all positions, particularly on the working strokes of said plungers.

In order to determine the size of the control rings it becomes necessary, first to accurately plot the curvature of the theoretical curve or spiral which is the locus of all points of tangency to which the axes of the plungers are normal in the several angular positions of said plunger. In plotting this curve the following equation has been developed in which a predetermined length of stroke has been assumed as being π times the length "R" of the crank arm. With the plunger at the extreme end of the in-stroke the point on the eccentric ring which is located at the shortest distance from the axis of rotation of the cylinder block will be taken as the initial point "O" or origin. The distance from "O" to the point of tangency "T" on the circular path of the outer end of the crank arm will be the constant "C", and must also be of sufficient length to accommodate the length of stroke

(π multiplied by "R"). Then any position along the control spiral can be plotted by solving the equation

$$5 \quad L = \sqrt{\left(\frac{\pi RA}{180} + C\right)^2 + R^2}$$

in which—

10 L = the length of a line from the axis of rotation of the cylinder block to the required point on the control spiral.

15 A = the angle between the position of the crank arm in the original position of the plunger when the outer end thereof is at "O", and the position of said crank arm when the plunger is in any other position, 20 when the angle "A" is less than 180° .

This equation applies either way through 180° of arc from the initial point of origin "O".

25 It will be found by solving this equation that the center lines of the cylinders will always be normal to the control spiral through 180° arc of operation, and the movement of the plungers will be uniform for any equal number of degrees of arc of travel of the outer end of the crank arm.

The control spiral, plotted for an entire revolution of the cylinder block has the form of a heart-shaped curve which is incidentally 30 shown in figure 8, having the two lobes *a* and *b* intersecting at the points *c* and *d* which may be termed "neutral points" since they occur respectively at the inner and outer limits of the range of travel of the 35 plungers at which points there is practically no movement of the plungers. A curve of this shape is purely theoretical, however, and a circular control ring will probably have to be chosen for practical operativeness, so 40 that the ideal control ring is that circle which most closely coincides with the theoretical control spiral, the latter being shown in heavy dotted lines in Figure 8. It will be noted that the greater variations of the 45 circle and spiral are at points which I have indicated neutral arcs, adjacent the neutral points *c* and *d*. By the adoption of the circle as a control practically the same angularity of the cylinders relative to this 50 circle is maintained as in the case of the spiral except in the neutral arcs. This fact, coupled with the fact that there is practically no movement of the pistons as they travel through the neutral arc is an advantage in 55 that these are the periods when the inlet and outlet ports are closed by the divisional walls of the bulb, and as the piston movement is zero there is no compression or vacuum formed in the cylinders during this period of operation.

60 For the purpose of enabling the rotor to start without load it may be advantageous to provide means for shifting the axis of the eccentric ring relative to the axis of rotation of the cylinder block. One way of carrying

out this feature is to provide the sides of the frame 1 with parallel slots 27 so arranged as to receive the stud bolts 28 which project, preferably at equal intervals from the outside face of the eccentric rings. The eccentric ring is also provided with a stem 29 extending through an aperture in the end of the frame and being advanced and retracted by means of the shift nut 30. The range of movement of the eccentric ring afforded by 70 the length of the slots 27 and of the shift nut is such that the axis of the eccentric ring and cylinder block can be made to coincide. When said axes are in coincidence there is no reciprocatory movement of the plungers and the load on the pump or converter is nil. 75 By screwing the shift nut an appropriate distance in either direction the length of stroke of the plungers may be regulated, determining the capacity of the rotor. Nuts 80 31 upon the stud bolts 28 are adapted to be tightened against the side of the frame to hold the eccentric ring in any position of adjustment. It is of course to be understood that the means here shown and described, for 85 accomplishing the shifting of the eccentric ring is merely illustrative of other means which may be employed for accomplishing a like result.

90 While the one stage pump or converter, as above described is probably the preferred and most universal adaptation of the invention, there are some cases, especially where it is desired to discharge against back pressure to avoid loss of head, or in the design of a 95 compound steam engine, preferable to use two or more stages, substantially identical with the single stage converter, and coupled together in cooperative relation.

100 A two stage motor, the object of which is the avoidance of loss of head, is shown in Figures 8 to 12 in which the hollow hub 35 is formed with a ported enlargement 36 about which the two stages of the rotor are 105 grouped in the manner now about to be described. The hub 35 is fixed in any suitable manner to the frame the latter being formed in part of the plates 37 and 38 which carry the respective eccentric rings 39 and 40. 110 The enlarged intermediate portion of said hub is preferably spherical in contour, forming a valve surface closely embraced by the cylinder blocks 41 and 42, said blocks being formed with complementary spherical 115 faces and being held in position by means of end thrust-bearings 43. The cylinder blocks in this instance, may be similar to the cylinder blocks described in the one stage embodiment of the invention, except as they have been necessarily modified to suit the 120 cooperating structure. In the present instance four cylinders, 44, are shown for each stage, said cylinders being arranged with their axes tangential to a circle the radius of 125 which represents the crank arm of the rotor. 130

Plungers 45 reciprocate in said cylinders, said plungers being provided with pins 46 projecting from the outer sides thereof and through slots 47 in the cylinder walls. Connecting plates 48 are journalled at their outer ends upon the pins 46 said connecting plates, in the present illustrative embodiment of the invention being individual to the cylinders.

Said connecting plates are apertured in 10 the same manner as the connecting plate illustrated in Figure 4, the connecting plates for each stage of cylinders being journalled upon the respective eccentric control rings 39 and 40 by means of the roller or other 15 appropriate bearings 49. The external diameter of the eccentric control rings is that of the circle which most nearly coincides with the heart-shaped spiral *a*, *b* shown in Figure 8.

20 Packing means 50 which is preferably somewhat yielding in character is inserted between the cylinder blocks 41 and 42 adjacent the intermediate enlargement upon the hub 35, and the cylinders of the respective 25 stages are connected at their outer ends by connections 51 through which power is transmitted from the driving stage to the driven stage. These connections may be semi-flexible in nature, and, cooperating with the 30 packing 50 permit of nice adjustment of the cylinder blocks with respect to the spherical enlargement of the hub. Said adjustment is effected by screwing up the end-thrust bearings 43.

35 The hub 35 is bored from either end toward the center, a partition wall 52 separating the bores. The bore on one side forms an inlet passage 53, that on the other side an outlet passage 54, said passages opening in the surface of the spherical enlargement as inlet and outlet ports 55 and 56 respectively. The inlet port 55 serves the 40 stage of cylinders constituted by the cylinder block 41 and the outlet port 56 serves that 45 stage of cylinders included in the cylinder block 42. The central enlargement is also provided with a port 57 serving as an outlet for the cylinder block 41 said port being connected by a passage 58 with a port 59 50 the latter comprising an inlet for the cylinder block 42. It will readily be appreciated from what has been described that the course 55 of fluid entering by the port 55 will lead through the cylinders associated with the cylinder block 41 and then, by way of the passage 58 through the cylinders of the cylinder block 42 the final discharge being by way of the outlet port 56 and the bore 54. It will be observed from Figure 8 that the 60 cylinders of each block are oppositely arranged, and that the two-phase rotor is exactly reversible so that, if desired, the bore designated as the outlet in this description may in practice be the inlet.

65 Referring now more in detail to the pas-

sage of fluid under pressure into the rotor by way of the port 53, so that the rotor is functioning as a motor, the actuating medium enters one of the cylinders of the first or driving stage, said cylinder being designated by the reference character *m* in Figure 8 said fluid forcing the plunger of said cylinder outwardly, substantially normal to the eccentric control ring, and re-acting against the cylinder block tangentially of 70 the circle representing the path of its crank arm, rotating the cylinder block clockwise and thereby at the same time causing the outward movement of the plunger in the cylinder. Said plunger continues its outward movement until it reaches the neutral point *d*, which position is shown with reference to the plunger of the cylinder *n* in Figure 8. When the cylinder *m* reaches this position the inlet port is cut off from the cylinder by the divisional wall within the enlargement of the hub. As rotation continues the cylinder opens to the outlet port 57, the plunger at the same time moving inwardly along the control ring and discharging the contents of the cylinder through the outlet port 57, through the passage 58 into the inlet port 59 of the second or driven stage, with which port a cylinder in the second or driven stage is in communication. During the rotation of the cylinder *m* from the lower neutral arc to the higher one, the plunger is returned into the cylinder by the connecting plate, but as the piston in the communicating cylinder of the second stage 85 recedes in its cylinder at equal velocity there is practically no compression in either cylinder, therefore the passage of the actuating medium from the first to second stage is accomplished with very little pumping effect 90 and with practically no loss in efficiency other than friction. It will be noted that the two stages operate as one unit, at the same speed and held in the same relative 95 positions by means of the connections 51 or other convenient means which permit of the adjustment of the intervening space. While in the illustration but one cylinder of each stage is shown communicating with the bypass at the same time the operation of the 100 motor is not affected should a plurality of 105 cylinders of the respective stages be concurrently in communication.

110 In the second or driven stage the cylinders are placed tangent to the same sized control ring as in the first stage, but pointed in the opposite direction. Now as a cylinder of the second stage rotates clockwise from the upper neutral arc, the plunger moves outwardly in the cylinder, the actuating medium following the displaced space in the cylinder until the cylinder reaches the main neutral arc where the inlet port is closed. It will be observed that as the cylinders 115 rotate clockwise from the lower neutral arc to 120

the upper neutral arc they remain on radial lines, and therefore normal to the control circle through practically the entire 180°. From the lower neutral arc to the upper neutral arc the plunger is moved inwardly, which in turn discharges the actuated medium outwardly through the port 56. The operation above described accomplishes the following functions in sequence; the energy 10 in the actuating medium is transmitted to the first or driving stage, carried to the second stage by direct communication through the by-pass and discharged from the second stage with no loss of energy except such as is absorbed in friction.

Any convenient means may be provided for transmitting power, or what amounts to the same thing, motion, from either stage of the rotor to any device designed to be 20 driven. Said means are exemplified in the present invention in the form of a gear attached in any suitable manner to the cylinder block 42 and meshing with a gear 60 on a stub shaft 61 mounted in a bearing in 25 the plate 38 and extending to a point without the frame of the motor at which point it carries a gear 62 adapted to be suitably connected to the driven mechanism. It is obvious that a two stage rotor of the class 30 described is especially adapted to the direct measurement of the flow of liquids without materially affecting the head or pressure of said liquid. While other means may be adopted for constituting the valved relation 35 between the hub 35 and cylinder blocks I have found that the spherical shaped bar has two distinct advantages over other forms of bearing, first the contact of the revolving cylinders is maintained very uniform 40 throughout the contact area, due to the fact that fluctuation of the true plane of rotation does not open the contact on one side and bind on the other; secondly, any tendency of the revolving parts to drift along the 45 axis of rotation is taken up by the normal contact near the shaft before any binding effect is produced at other points of contact.

I consider that my invention, resides 50 mainly in the broad aspects hereinbefore set forth, and only secondarily in the details of construction and arrangement, whereupon I do not restrict myself to the particular construction here disclosed, but only by the 55 terms of the claims and the state of the prior art.

Having described my invention what I claim as new and desire to secure by Letters Patent, is:—

1. A rotor comprising one or more cylinders having the longitudinal axes thereof arranged tangential to a circle concentric with the axis of rotation of the rotor, a relatively fixed eccentrically mounted guide ring, and plungers within said cylinders re-acting

against said guide ring in lines of force 65 which are substantially radial to said guide ring throughout the working stroke of said plungers.

2. A two stage rotary motor comprising 70 a rotor consisting of a pair of cylinder blocks each including one or more cylinders having the longitudinal axes thereof directed tangential to a circle concentric with the axis of rotation of the rotor, the cylinders of the respective blocks being reversely arranged with respect to one another, plungers in said cylinders, eccentrically mounted guide rings against which said plungers re-act in causing relative reciprocation between said plungers and cylinders, means for admitting 80 fluid to the cylinders of one block and discharging it from the cylinders of the other, the cylinders of one block when on the inward stroke being in communication with the cylinders of the other block which are 85 at the same time on the complementary phases of the outward stroke.

3. A two stage rotary motor comprising 90 a rotor consisting of a pair of cylinder blocks each including one or more cylinders having the longitudinal axes thereof directed tangentially to a circle concentric with the axis of rotation of the rotor, the cylinders of the respective blocks being reversely arranged with respect to one another, plungers in said cylinders, eccentrically mounted guide rings one to each cylinder block, the plungers of each cylinder block re-acting 95 against the guideway associated with that block, guide rings in lines of force substantially radial to the guide ring throughout the working stroke of said plungers, means for admitting fluid to the cylinders of one block and discharging it from the cylinders 100 of the other, the cylinders of one block when on the inward stroke being in communication with the cylinders of the other block which are at the same time on the complementary phases of the outward stroke.

4. A rotary motor comprising a frame, a hub fixedly carried by said frame, said hub being formed with a portion having spherical curvature, said hub being provided with inlet and outlet passages opening into the surface of said spherical portion forming 115 inlet and outlet ports, a rotor rotatably mounted upon said hub including a pair of connected cylinder blocks and having cooperating spherical faces embracing the spherical portion of the hub and seated thereupon, each cylinder block including one or more cylinders having the longitudinal axes thereof directed tangentially to a circle concentric to the axis of rotation of the rotor, the cylinders of the respective blocks being reversely arranged with respect to one another and opening upon said spherical faces forming ports, plungers in said cylinders 120 and

ders, eccentrically mounted guide rings against which said plungers re-act when reciprocating relative to said cylinders, means for admitting an actuating medium to the cylinders of one block and discharging it from the cylinders of the other, the cylinders of one block when on the inward

stroke being in communication with the cylinders of the other block which are at the same time on complementary phases of 10 the outward stroke.

In testimony whereof I have hereunto set my hand.

CLIFFORD HASTY KAIN.
